Specification for Design.

Patented May 23, 1922.

Application filed September 29, 1921. Serial No. 504,264. Term of patent 14 years.

To all whom it may concern:

Be it known that I, FRANK A. CIGOL, a citizen of the United States, residing at Paterson, in the county of Passaic and State of New Jersey, have invented a new, original, and ornamental Design for a Toy Ball, of which the following is a specification, reference being had to the accompanying drawing, forming part thereof.

The drawing shows a toy ball embodying my new design. The surface of the ball is divided by an equatorial band α , and each

hemisphere is divided into sectors having projecting nubs b , the sectors in each hemisphere being spaced from each other and these spaces being occupied by nub-groups c in each of which the nubs are conventionally arranged around a common center.

I claim:

The ornamental design for a toy ball, as shown and described.

In testimony whereof I affix my signature.

FRANK A. CIGOL.
